UNITED STATES PATENT OFFICE.

ENGLAND J. BARKER, OF MORGAN PARK, ILLINOIS.

AUTOGRAPHIC REGISTER.

SPECIFICATION forming part of Letters Patent No. 761,436, dated May 31, 1904.

Application filed December 7, 1903. Serial No. 184,134. (No model.)

To all whom it may concern:

Be it known that I, ENGLAND J. BARKER, a citizen of the United States, and a resident of Morgan Park, in the county of Cook and State 5 of Illinois, have invented certain new and useful Improvements in Autographic Registers, of which the following is a full, clear, and exact description.

Heretofore autographic registers have generally been constructed so as to provide a memorandum for the purchaser, the cashier, and the proprietor of each transaction recorded. The ends of the strips of paper on which the memorandum for the purchaser and cashier are written are torn off; but the continuous strip upon which the private memorandum for the proprietor appears is rolled up on a receiving-roller that is constructed so as to be capable of removal from the machine whenever desired. Oftentimes it happens that after such a three-record machine has been used for a while it is decided to use but two of such records—one for the purchaser and one for the cashier—and in this case it is either necessary to run the three rolls of paper in the machine or buy a new register.

The object of my invention is to provide a simple, cheap, and economical means for converting whenever desired a three-record machine into a two-record machine or, should it subsequently become desirable, to change the machine back to a three-record machine again, or, if desired, instead of the two issue and one record strip the register may provide three issue strips. This I accomplish by the means hereinafter fully described and as particularly pointed out in the claims.

In the drawings, Figure 1 is a side elevation of an automatic register having my improvements applied thereto. Fig. 2 is a longitudinal vertical section of the same. Fig. 3 is a plan view showing one end of the same in horizontal section in the plane indicated by dotted line 3 3 in Fig. 1. Fig. 4 is a detail view illustrating the pawl and ratchet used in conjunction with the receiving-roller. Fig. 5 is a perspective view of the crank used in connection with my improvements.

The features of an autographic register,

mention of which are necessary to a thorough 50 understanding of my invention, are the case, the paper-rolls, the bed, the draft-rollers, and the receiving-roller. The case of the register shown in the drawings comprises a base-plate A, a frame for housing the operative parts 55 consisting of a stationary body-section B, and a movable section C, hinged thereto at one end of the register. It is immaterial how these sections are made. As shown in the drawings the side walls of these sections are preferably 60 parallel throughout the length of the register, and the lower edges of the side walls of the movable section normally rest and are supported upon the upper edges of the reduced portion of the side walls of the stationary section. In the register shown in the drawings the stationary section B has two rolls of paper 65 a and b journaled therein, and the hinged or movable section C has one roll c journaled therein, and when the case is closed the axes 70 of these rolls are preferably all in the same horizontal plane and are located approximately an equal distance apart. The paper from these rolls extends to and around the guide-rolls d d' d'', journaled in the rear extensions of the side walls of the movable section C of the case, and then extends forward over the horizontal bed or flat platform D, connecting said side walls and forming the top of 75 section C. At the forward end of this platform D, which provides a background and supports the paper when the operator writes upon the same, are two rollers E and F, whose bearings are journaled in the side walls of 80 said section C, one above the other, which come 85 in contact in about the same horizontal plane as the upper surface of platform D, so that the three strips of paper from rolls a, b, and c pass between them. The undermost strip of paper, upon which the private record of the 90 proprietor is kept, extends from between rolls E and F downward and forward to and around a removable roller G; but the ends of the two uppermost strips of paper, upon which are the record of the transaction for the cashier and 95 purchaser, are left free after they leave rollers E and F, so that they can easily be torn off.

Heretofore the roller E and the receiving-

roller were connected by gearing, and the journal of one of these rollers, generally that of roller E, was extended through its bearings and a crank permanently secured there-
 5 to. In consequence the operation of the machine required the employment of the strip of paper upon which the private record was made, because this strip is the draft-strip—that is, it is the only strip that has its ad-
 10 vance end wound upon a receiving-roller, which when revolved draws or pulls the strip and assists in the carrying forward of the other two strips. Now my invention dis-
 15 penses with the gearing connecting the roller E and the receiving-roller and requires that the journals *e* and *g* of both rollers E and G shall extend through their respective bearings and said extensions provided with screw-threaded ends and also requires a crank H,
 20 the boss of which has an internal screw-thread which after it has been screwed onto either of the extensions *e* and *g* by a right-to-left movement will by a continuation of such movement revolve the roller to whose extension it is attached and will when revolved in the opposite direction, or from left to right, unscrew from said extension. I prefer in order to prevent these rollers E and G from reversing when the handle is being removed from
 25 their extensions to provide each with a ratchet and pawl. The roller G has its ratchet I secured to the journal of the same just inside of its bearings, and this ratchet is engaged by a pawl *h*, which is pivoted to the inner
 30 surface of the side frame of the section C in such position as to engage said ratchet. As hereinbefore stated, this roller is removable. This removability can be accomplished in any suitable manner; but, as shown in the
 35 drawings, the head *m* of the roller from which the extension *g* projects is the same diameter as the roller itself and is secured rigidly to the extension *g* in the manner shown in the drawings, Fig. 3, so as to leave a groove or circumferential slot *n* between said ratchet and head. A spring-pressed plate *o* normally
 40 engages this slot *n* thereby retaining the extension and its co-operating parts in their proper position, and in order to lock said ex-
 45 tension to the roller G and prevent their turning separately a tenon *p* is provided on the ratchet and a corresponding groove in the roller. When it is desired to remove roller G, the plate *o* is pushed out of slot *n* and the extension then pulled out of the roller, which latter may be then removed through the end of the register-frame, which has been previously opened. The roller E has its ratchet *h* preferably secured to its extension
 50 *e* just outside the case next its bearings, and the pawl *K*, engaging this ratchet, is pivoted to the outside of the side wall of section B in such position as to properly engage said ratchet.

In operation when it is desired to make a

memorandum of each transaction for the pur- 65 chaser, the cashier, and the proprietor the crank H is attached to the extension *g* of the roller G and turned in the proper direction to wind up the strip of paper upon which the record for the proprietor is made. In this case the proprietor's record acts as a draft 70 web or strip and draws with it the other two records through the rollers E and F, so as to enable the cashier's and purchaser's record of the transaction to be torn off. When only 75 two records—namely, one for the purchaser and one for the proprietor—are required, the strip of paper to be wound upon the roller G is cut between said roller G and rollers E and F and, if desired, one of the rolls of paper 80 removed from the machine, substantially in the manner shown and described in Letters Patent of the United States No. 733,934, granted to me July 23, 1903. The handle is then removed from the extension *g* of roller 85 G and attached to the extension *e* of roller E, and the friction of the rollers E and F is depended upon to draw the strips for the records of the purchaser and the proprietor forward between them, so that they can be torn off. 90

What I claim as new is—

1. An autographic register comprising a platform; means for supplying strips of paper in the same direction over the same; a non-reversible receiving-roller adjacent to the discharge end of said platform, having one of its journals extending through its bearings beyond the side of the case of the register; non-reversible compression-rollers between said platform and receiving-roller, one of which has one of its journals extending through its bearings; and a crank separately engaging the extension of said compression and receiving rollers for independently revolving the same. 105

2. An autographic register comprising a platform; means for supplying strips of paper in the same direction over the same; a receiving-roller adjacent to the discharge end of said platform, having one of its journals extended through its bearings and screw-threaded; and a ratchet and pawl connected thereto to prevent the reverse motion thereof; compression-rollers between said platform and receiving-rollers, one of which has one of its journals extended through its bearings and screw-threaded; a ratchet and pawl connected to said compression-roller and preventing the reverse motion thereof; and a crank for engaging the journal extension of said receiving-roller or of said compression-roller independently of the other. 115

3. An autographic register comprising a platform; means for supplying strips of paper in the same direction over the same; a non-reversible receiving-roller adjacent to the discharge end of said platform, having one of its journals extending through its bearings be- 120 125

yond the side of the case of the register; non-reversible compression-rollers between said platform and receiving-roller, one of which has one of its journals extending through its 5 bearings; and a crank engaging the extension of either said compression or receiving roller for independently revolving the same.

In testimony whereof I have hereunto set my hand this 18th day of November, 1903.

ENGLAND J. BARKER.
